PORTABLE PRESSING TABLE

Otto Frej, Toflund, Denmark

Application September 19, 1949, Serial No. 116,603
In Denmark August 26, 1948

3 Claims. (Cl. 38—137)

1

The present invention relates to a pressing table having a cushioned perforated surface on which clothes are pressed with employment of a damped pressing cloth that is applied between the clothes and the hot pressing iron.

More particularly, the invention relates to pressing tables of the kind in which the pressing surface is constituted by the top wall of a chamber to the bottom of which there is connected a suction device for exhausting the steam developed in the pressing operation through the perforated pressing surface and the cushioning thereof. The said suction device consists as rule of a fan driven by an electric motor.

Pressing tables of the kind specified are known, in which the motor and the suction device are mounted either on the base member of the pressing table, or, if the pressing table is supported on a frame, then exteriorly of the latter. These known pressing tables suffer from the serious drawback that they require too much space, and that the motor with the suction device connected thereto are likely to interfere with the clothes to be pressed and are also subject to damage when the pressing table is moved from one place to another in the room in which it is used.

It is essential for the universal and all round employment of a pressing table in larger and smaller tailor's shops that the outer dimensions of the pressing table should be as small as possible, and that the table should occupy the smallest possible floor area.

These requirements have not been sufficiently considered in the constructions of pressing tables so far in use. It is therefore desirable to construct a pressing table of the kind specified in such a manner that it has an outer configuration convenient for the operation thereof and also has a relatively low weight so that it can easily be moved by a single person. Moreover, the pressing table should be simple to operate and should not present laterally projecting parts that might catch or strike other objects when the pressing table is moved, which is as a rule frequently done, particularly in rooms where a number of persons work and employ one and the same pressing table.

According to the present invention, in order to fulfill the above mentioned requirements, the suction device and the electric motor operating same are mounted directly on the underside of the pressing table between legs supporting same, the pressing table being constructed as a chamber with a perforated, cushioned top wall. Here-

2

by it is obtained that the suction device and the electric motor do not increase the outer dimensions of the pressing table except by determining the minimum height thereof above the floor, and further the motor and the suction device will be in a protected position.

In an advantageous constructional form of a pressing table according to the invention, the suction device is in the form of a fan mounted in a recessed portion of the bottom wall of the pressing table, while the motor is enclosed within a casing in the form of a deep bowl mounted on the underside of the pressing table and provided in its bottom wall with perforations through which the mixture of steam and air exhausted from the said chamber by the suction device is passed to the surrounding atmosphere.

To enable the operator to start or stop the said motor without leaving the pressing table, it is advantageous to arrange a switch for this purpose on the pressing table itself, and this switch may suitably be constructed in such a manner that it can be operated by tilting or lifting the pressing table itself so that one of legs of the pressing table is lifted from the floor, whereby a rod mounted at one end of the pressing table is displaced and operates the switch when the said leg is again applied to the floor, the switch being suitably constructed in such a manner as to be alternately opened and closed by such operation. The operator then just has to lift and then again lower one of the legs of the pressing table in order to close and open the feeding circuit of the motor.

The perforated, cushioned top surface of the said chamber, the steam exhausting chamber, may suitably be provided with grooves between the individual perforations, whereby it is obtained that an efficient suction takes place, not alone through the portions of the cushioning or the clothes applied thereto located immediately above the perforations, but also through the portions of the clothes located above the grooves. Thus, with a given number of holes in the pressing surface, the suction area is increased and the flow resistance to be overcome by the suction device consequently lowered, or, alternatively, with a certain flow resistance, the number of holes may be selected lower than would otherwise be possible.

The invention will now be described in further detail with reference to the accompanying drawing in which,

Fig. 1 shows a longitudinal section through one form of an ironing board according to the

invention, taken along the line II—II of Fig. 2,
Fig. 2 an end view of same
Fig. 3 a plan view of same, and

Fig. 4 a section through a detail of the ironing board, taken along the line III—II of Fig. 1.

1 is an elongated, substantially bulb-shaped hollow body consisting e. g. of a light metal alloy, and the top surface of which forms the pressing surface of a pressing table consisting of the said hollow body and three legs 2, 2 and 20 supporting same. The top surface of the hollow body is provided with a covering 3 of a heavy woolen fabric held in position on the hollow body in known manner by means of a wire coil 40 sewn into a running stitch. The clothes to be pressed are applied to the surface of the covering, and in the pressing operations, use is made of a damp pressing cloth developing steam during the pressing operation. This steam is exhausted through holes 4 in the top wall of the hollow body 1 by means of a fan 6 driven by an electric motor 5 and forming a suction device by means of which the steam developed during pressing is exhausted through the openings 4, and further through a central opening 7 in the bottom wall of the hollow body formed by the pressing table. The motor 5 is enclosed within an outer casing 8, consisting of a light metal alloy or another suitable material and fixed by means of screws 9 to a cylindrical flange 10 projecting from the underside of the pressing table and within which the fan is arranged. The motor is suspended on a supporting member 11, Fig. 4, inserted in the flange 10 and fixed to the latter by means of screws 12. The supporting member 11 has four radially inwardly directed projections 13 spaced at 90° and serving to support lugs 14 on the outer side of the motor casing, the said lugs 14 being each received in a groove in the inwardly facing side of an individual one of the projections 13, which grooves are cushioned with a vibration-damping material 15 such as rubber as seen in Figs. 1 and 4.

When the screws are released, the supporting member 11 may be withdrawn together with the motor and the fan 6, so that these parts become easily accessible, and the motor may be detached from the supporting member 11 by turning the motor casing about the axis of the motor, as will be directly seen.

At the bottom end of the casing 8, holes 16 are provided through which the steam exhausted from the pressing table by means of the fan 6 and thence down through the casing 8 is passed to the surrounding atmosphere.

The motor 5 may be provided in known manner with a loose cable having a plug, by means of which the motor may be connected to a corresponding wall socket of an electric installation. For closing and opening the feeding circuit of the motor through such a movable cable, a conventional switch forming a part of the permanent installation may be used, but the closing and opening of the feeding circuit of the motor may also be effected by means of a special electrical switch 17, Fig. 1, arranged inside the chamber formed by the hollow body 1 and controlled by means of a push rod 18 extending into the said chamber through one of the three legs of the pressing table. The switch 17 may suitably be of the known kind having a push button 19 for the operation thereof, and designed to be alternately closed and opened upon successive operations of the push button. The rod 18 extends through a tubular leg 20 of the pressing table and

is rigidly connected or integral with a foot 21 on which the said leg is supported when the table is in use. If this leg is slightly lifted from the floor, the rod 18 with the foot 21 are displaced away from the push button, and when the leg is then applied to the floor, the rod 18 is pushed inwards in the leg 20 and thereby acts on the push button 19 to operate the switch. If the end of the pressing table, at which the leg 20 is provided, is subsequently slightly lifted, the rod 18 will slide a distance out through the leg 20 and thereby away from the push button under the influence of its gravity, if desired in combination with a spring (not shown), whereby the push button is permitted to move forwards through the casing of the switch, and when the considered end or corner of the pressing table is again lowered, so that the foot 21 again presses the rod 18 into the leg 20, the push button 19 is again displaced to operate the switch 17 so as to close or interrupt the circuit of the motor, as the case may be.

In the upper side of the hollow body constituting the pressing table, grooves 22 may be provided between the holes serving to exhaust the steam developed in the pressing operation. These grooves 22 form shallow passages connecting the outer ends of the said holes and thereby increasing the area on the upper side of the covering 3, through which the suction caused by the fan 6 acts on the clothes that are being pressed. Hereby it is obtained that the suction is effective on a larger area of the clothes, and that the resistance to the flow of the steam is consequently reduced as compared with the resistance that would be present if the grooves were not provided.

I claim:

1. An ironing board comprising an elongated hollow body having a top wall and a bottom wall defining a cavity therebetween, a plurality of spaced apertures being formed in said top wall, an opening formed in said bottom wall, an electric motor arranged in a vertical position below said opening, an annular flange adjacent the circumferential edge of the said opening, a fan located within the space surrounded by said flange and attached to the shaft of said motor, a number of radially disposed spaced projections on the inner surface of said annular flange, a number of radially disposed lugs on the external circumferential face of said electric motor arranged each to engage one of the said projections within the said annular flange to support the motor on same, a groove in the inner face of each of the radially disposed spaced projections supporting the motor, arranged to receive an individual one of the lugs on the external surface of the motor, when the latter after having been brought to a position in which the lugs are received in the spaces between said projections, is turned about its axis, and a cushion of a vibration-damping material arranged in each of said grooves to bear against the adjacent faces of said projections and said lugs.

2. An ironing board comprising an elongated hollow body having a top wall and a bottom wall defining a cavity therebetween, a plurality of spaced apertures being formed in said top wall, an opening formed in said bottom wall, an electric motor arranged in a vertical position below said opening, an annular flange adjacent the circumferential edge of the said opening and extending inwardly as well as outwardly from said edge, a fan located within the space sur-

rounded by said flange and attached to the shaft of said motor, a number of radially disposed spaced projections on the inner surface of the outwardly extending portion of said annular flange, a number of radially disposed lugs on the external circumferential face of said electric motor arranged each to engage one of the said projections within the said annular flange to support the motor on same, a groove in the inner face of each of the radially disposed spaced projections supporting the motor, arranged to receive an individual one of the lugs on the external surface of the motor, when the latter after having been brought to a position in which the lugs are received in the spaces between said projections, is turned about its axis, and a cushion of a vibration-damping material arranged in each of said grooves to bear against the adjacent faces of said projections and said lugs.

3. An ironing board comprising an elongated hollow body having a top wall and a bottom wall defining a cavity therebetween, a plurality of spaced apertures being formed in said top wall, an opening formed in said bottom wall, an electric motor arranged in a vertical position below said opening, an annular flange adjacent the circumferential edge of the said opening and extending inwardly as well as outwardly from said edge, a fan located within the space surrounded by the portion of the said annular flange extending inwardly from the said opening and at-

20 tached to the shaft of said motor, a number of radially disposed spaced projections on the inner surface of the outwardly extending portion of said annular flange, a number of radially disposed lugs on the external circumferential face of said electric motor arranged each to engage one of the said projections within the said annular flange to support the motor on same, a groove in the inner face of each of the radially disposed spaced projections supporting the motor, arranged to receive an individual one of the lugs on the external surface of the motor, when the latter after having been brought to a position in which the lugs are received in the spaces between said projections, is turned about its axis, and a cushion of a vibration-damping material arranged in each of said grooves to bear against the adjacent faces of said projections and said lugs.
